UNITED STATES PATENT OFFICE.

EUSTACE CREEES AND CHARLES S. COURT, OF PROVIDENCE, RHODE ISLAND,
ASSIGNORS TO THE WAITE, THRESHER COMPANY, OF SAME PLACE.

DESIGN FOR A HANDLE FOR BUTTON-HOOKS OR SIMILAR ARTICLES.

SPECIFICATION forming part of Design No. 28,554, dated May 10, 1898.

Application filed February 25, 1898. Serial No. 671,695. Term of patent 3½ years.

To all whom it may concern:

Be it known that we, EUSTACE CREEES and CHARLES S. COURT, citizens of the United States, residing at Providence, in the county of Providence and State of Rhode Island, have invented and produced a new and original Design for a Handle for Button-Hooks or Similar Articles, of which the following is a specification, reference being had to the accompanying drawings, forming a part thereof.

Figure 1 represents a side view of a handle showing our new design. Fig. 2 represents a longitudinal section of the handle.

As shown in the drawings, the leading or material features of our design consist in the transverse circular bead *a* at the inner end of the handle, the foliated scrolls *b b*, extending from the bead *a* to near the outer end of the handle, which is terminated by the representation of a flower *c*, having incurved petals *d*, surrounded by outwardly-spreading petals *e*, the said foliated scrolls *b b* being first brought toward each other at *f*, then spread outwardly at *g*, then brought toward each other at *h*, and then spread outwardly and turned inwardly at the base of the flower *c*. Between the inwardly-turned ends of the foliated scrolls *b b*, at the base of the flower *c*, is arranged the scroll *i*, which, with the scrolls *j* and *k*, form the boundary of the oval convex panel *l*. A

stem *m* is traced from the inner end along the body of the handle to the flower *n*, having the incurved petals *o* and the outwardly-spreading petals *o'*, a flower *p* being shown at the starting-point of the stem and the buds or 35 opening flowers *p' p' p'* shown along the continuation of the stem, with the leaves *q q'* shown under the flower *n* and the leaves *r r'* above the same, and between the leaves *r r'* and the foliated scroll *k* are arranged the 40 flowers *s s'* and the leaves *t t'*, and between the sides of the panel *l* and the foliated scrolls *b b* are arranged the flowers *u u'*, and under the flower *u'* is shown the small leaf *v*.

In general outline the handle is oval in 45 cross-section at its wider portions, one-half of a longitudinal section being represented in Fig. 2.

Having described our invention, what we claim as new, and desire to secure by Letters 50 Patent, is—

The design for a handle for button-hooks and similar articles, herein shown and described.

EUSTACE CREEES.
CHAS. S. COURT.
